Thomas Walter Horn, University Heights, Ohio

Application April 15, 1933, Serial No. 666,298

14 Claims. (Cl. 101—218)

This invention relates to improvements in offset printing machines, particularly units for offset printing which are so designed and constructed as to be capable of being mounted in a known stencil printing machine in place of the cylinder of that machine, so that by having interchangeable stencil and offset printing units, either type of printing may be performed at different times upon a single machine. The invention in many of its aspects, however, is capable of general application.

One of the objects of the invention is the provision of an offset printing machine of simple construction which may be manufactured at low cost.

Another object is the provision of a unit of the character described which may be readily substituted for a portion of a known stencil printing machine, the remaining portions of the stencil printing machine being utilized, in connection with the substituted unit, for performing offset printing.

Another object is the provision of an offset printing machine capable of using "dry" ink, that is ink which, because of its chemical constituents, is capable of absorbing the necessary moisture from the atmosphere.

Another object of the invention is the provision of a novel mechanism for inking the plate upon the plate cylinder, and locating that mechanism within the hollow blanket cylinder, means being provided for disabling the inking mechanism while the two cylinders are in engagement for transferring an image from the plate cylinder to the blanket cylinder.

Another object is the provision of means for supplying moist air continuously to the ink on the inking mechanism.

Still another object is the provision of throwing out means for the plate cylinder, which shall be automatically operated when a lever is moved from one position to another, such lever being so located in the special embodiment of the invention herein illustrated as to be operated by sheet detector mechanism employed in the stencil machine with which the present invention is primarily intended to be used.

A further object of the invention is the provision of a printing plate with novel reenforcements at its ends and a novel and simple means for clamping the plate and drawing it taut over the surface of the plate cylinder.

Other objects and features of novelty will appear as I proceed with the description of that embodiment of the invention which, for the pur-

poses of the present application, I have illustrated in the accompanying drawings, in which

Fig. 1 is a view, principally in longitudinal vertical section, of a printing unit embodying the invention.

Fig. 2 is a transverse vertical sectional view taken substantially along the line 2—2 of Fig. 1.

Fig. 3 is a side elevational view of the unit.

Fig. 4 is a detail sectional view taken substantially along the line 4—4 of Fig. 3.

Fig. 5 is a transverse sectional view of the plate cylinder, showing the means which I employ for securing the ends of the plate and stretching it over the surface of the plate cylinder.

Fig. 6 is a detail sectional view, taken substantially on the line 6—6 of Fig. 4, illustrating a part of the plate cylinder throw-off mechanism.

Fig. 7 is a view similar to Fig. 1, but showing the cylinders in a different position, with the inking mechanism withdrawn out of contact with the plate cylinder, and with the impression cylinder withdrawn from printing position.

Fig. 8 is a detail elevational view showing a ratchet mechanism for advancing the fountain roll rotatably step by step.

Fig. 9 is a detail elevational view showing adjustable means for varying the size of the exit from the moisture dispensing container.

Figs. 10, 11 and 12 are detail views of the links which carry the inking rolls.

Fig. 13 is a fragmental detail sectional view on a larger scale, showing a portion of the inking mechanism, this view being taken substantially on the line 13—13 of Fig. 1.

Fig. 14 is a detail view of the same taken substantially on the line 14—14 of Fig. 13.

Fig. 15 is a further fragmental sectional view taken substantially on the line 15—15 of Figs. 1 and 14.

Fig. 16 is a fragmental sectional view taken upon the same section line as Fig. 4, but showing the plate cylinder in the throw-off position, that is separated from the blanket cylinder.

Fig. 17 is a fragmental side view similar to Fig. 3, showing the throw-off control mechanism in the position which it occupies when the plate cylinder is separated from the blanket cylinder.

Fig. 18 is a vertical sectional view showing in elevation the means which I employ for moving the oscillating rolls of the inking mechanism, and

Fig. 19 is a view illustrating a modified form of unit for use with ordinary lithographic ink.

In the drawings, I have represented in dotted lines a portion of a stencil printing machine 10, comprising side standards 11. An example of a

machine of this character, with which my unit may be employed, is disclosed more or less in detail in Patent 1,140,883, issued May 25, 1915 to A. B. Dick. The stencil cylinder ordinarily used with the machine is mounted in the standards 11, those standards having bearings 12 within which the shaft of such cylinder rotates. The stencil printing machine, as illustrated herein, also comprises a rubber-covered impression roller 13, mounted at its ends in a pair of levers 14, which are pivotally supported in the machine frame at 15, and are urged toward printing position by coil springs 16 or the like. One or both of the arms 14 may carry an anti-friction wheel 17 for a purpose later to be described.

When the stencil cylinder of the stencil printing machine has been removed from the bearings 12, an operation which can be readily and quickly performed, the unit constituting my invention may be substituted. This unit comprises a frame having end members 18 and 19 of disc form and a transverse member connecting the end members, said transverse member consisting of flat end pieces 20 and 21 secured to the members 18 and 19 respectively, a transverse vertical rib 22, a tray 23 and a sump 24 into which liquid is directed from the tray through the intermediacy of an inclined central trough 25. A threaded plug 26 at the bottom of the sump may be removed when required for clean-out purposes. At the centers of the end members 18 and 19 of the frame there are outwardly extending hubs 27 and 28 respectively. On the outer sides of these hubs I secure exterior frame members 29 and 30, the member 29 being held in place by a hollow nut 31 with a flange which engages the outer surface of the member 29, and the member 30 being held in place by a flanged pin 32 which is threaded into the hub 28. Cylindrical supporting elements 33 and 34 with outer knurled heads are projected through the bearings 12 and threaded tightly into threaded openings in the hollow nut 31 and pin 32, whereby the frame of the unit is clamped rigidly in place in the standards 11. It will be apparent from an inspection of the drawings that the center of gravity of the unit frame is well below the axis of the aligned supporting elements 33 and 34, and hence the force of gravity tends to maintain the frame parts of the unit in the positions in which they are disclosed in the drawings, and thereby reduces the work to be done by the threaded supporting elements 33 and 34 in holding the frame against rotation in the standards 11. Upon the hubs 27 and 28, between the inner and outer frame members, I mount rotatably my hollow blanket cylinder 35. This cylinder comprises end members 36 and 37 and the arcuate shaped casting 38, the latter having a series of inwardly extending fins or vanes 39. On the end member 37 there is a V-pulley 40 by means of which the cylinder may be power driven. It will be understood, however, that some convenient means for driving the cylinder by hand may be substituted if desired, or that any other suitable power means may be employed.

On the outside of the casting 38 there is secured a blanket 41, which may be of the usual rubber with fabric backing construction, and which may be secured to the casting in any convenient or known manner. A semi-cylindrical guard plate 42 of sheet metal may be mounted upon the transverse members of the frame, so as to define with the casting 38 an arcuate air passage. The vanes 39 moving through that passage produce a cur-

rent of air for a purpose which will presently appear.

In the outer frame members 29 and 30 I mount rotatably a plate cylinder 43, which is so positioned as to cause an offset printing plate 44 mounted thereon to contact with the blanket 41 for the purpose of transferring an image from the plate to the blanket. The plate cylinder comprises end members 45 and 46 and a cylindrical member 47, the latter having therein a longitudinal depression 48. Within this depression I mount a bar 49 upon pivots 50 in the end members 45 and 46. Adjacent one side of the recess 48 I form a shallow rabbet 51 in the cylindrical member 47, and I form a similar rabbet 52 in the outer face of bar 49. Reinforcements 53 on the ends of the printing plate 44 are received within the rabbets 51 and 52. These reinforcements extend along the end edges of the plate, and are flat, lying directly adjacent one surface of the plate. A reinforcement of this kind is a new departure in the art, and has the distinct advantage that it does not interfere with the filing of the plates in a flat condition. Preferably the reinforcements are formed by bending the metal of the flexible plate upon itself one or more times. The reinforcements are held in the rabbets 51 and 52 by means of clamps 54 and 55, the clamp 54 being mounted upon pivots 56 in the end members of the cylinder, and the clamp 55 being mounted upon pivots 57 carried by the bar 49. 58 are split ring springs positioned in annular recesses at the ends of the cylinder, and bearing upon the inner arms of the clamps 54 and 55, whereby the outer ends of those clamps are 35 swung into clamping position, and whereby the bar 49 with its clamp is swung about its pivot 50 toward the right in Fig. 5, thereby drawing the flexible plate 44 taut over the surface of the cylinder member 47. The springs 58 are shown in the drawings as of square cross section. This construction of plate and arrangement of plate securing and tensioning means permits quick and easy mounting or demounting of the plate, that is to say, a screw-driver or similar tool may be 45 thrust into the space between the clamps 54 and 55 and given a turn to swing the inner arms of the clamps away from each other, thereby swinging the outer arms of the clamps outward and permitting the plate reinforcements to be withdrawn from the rabbets 51 and 52, and the plate removed. When a new plate is to be mounted, the screw-driver or similar tool is operated in the same way, one end reinforcement is inserted into the rabbet 51, the plate is drawn around the cylinder, and the other end reinforcement placed in the rabbet 52, after which the screw-driver is withdrawn and the springs 58 act to clamp the plate reinforcements and draw the plate taut.

Inking mechanism.—The inking mechanism is carried by the end plates 18 and 19 of the frame, being located within the hollow blanket cylinder, thus utilizing space which would otherwise be wasted. This location of the inking mechanism within the blanket cylinder has the additional advantages of concealing the inking mechanism and protecting the clothing of the operator, as well as providing a nearly closed space within which a special atmosphere with the desired moisture conditions may be maintained, this being highly desirable for the "dry" ink which I prefer to employ.

59 is a fountain roll which is rotatably mounted in the end plates 18 and 19. Adjacent this roll there is a plate 60, the free edge of which runs

upon the surface of roll 59. The "dry" ink 61 is positioned between the plate 60 and the roll 59. The plate 60 includes a flexible portion and carries at its free end a cam surface against which 5 one or more pins 62 bear. These pins are threadably mounted in a rigid portion of the plate, so as to be adjustable longitudinally, and to bear with more or less force upon the cam surface at the end of the plate, to flex the latter in order 10 that the amount of ink taken up by the roll 59 may be controlled. This roll at one end carries a ratchet wheel 63 (Figs. 2 and 8). The roll shaft extends through the end plate 19 of the frame and carries a crank 64 upon the extremity of 15 which there is a follower 65 and a pawl 66. Upon the end member 37 of the blanket cylinder there is a cam 67 upon which the follower 65 runs. The follower 65 and the pawl 66 are carried upon opposite ends of a pin 68 at the end of crank 64, 20 the pawl on the inner side and the follower on the outer side of frame member 19, and the latter is provided with an arcuate slot 69 for the accommodation of the pin 68. It will be obvious that when the cam 67 engages the follower 25 65, the crank 64 is swung upwardly and the pawl 66 is thereby caused to rotate the ratchet wheel 63, and with it the roll 59, through a small angle. The extent of this rotation may be adjustably 30 regulated by means known in the art, as for instance by employing a guard plate over which the pawl 66 may be caused to run through part of its stroke.

The doctor roll of the inking mechanism is shown at 10. This roll is mounted in a pair of 35 links 71 (see Fig. 10) pivoted at 72 to the frame end members. The roll 10 turns upon a shaft which is mounted at 73 in these links. The links 71 may swing between the positions shown in Figs. 1 and 7. A second pair of links 74, Fig. 12, 40 mounted in the frame end members about pivot points 75, carry pairs of guides 76 between which the flattened ends of a shaft 77 are mounted. An inking roll 78 turns upon this shaft. In the links 74 there are formed circular openings 79. The 45 links 74 have formed therein arcuate slots 80 within which run rollers or other followers 81 carried at 82 in the links 71. The slots 80, being eccentric to the pivot points 75, it will be apparent that, as the links 74 swing from the position shown 50 in Fig. 1 to that shown in Fig. 7, the followers 81 will be drawn to the right and downward, thereby swinging the links 71 downward to the position indicated in Fig. 7, and pulling the doctor roll 10 out of contact with the fountain roll 59 and into 55 contact with the roll 78.

There is a third pair of links 82, Fig. 11, pivotally mounted at 83 in the frame end members. At the points 84 in their lower extremities these links carry a rod 85, see particularly Figs. 13, 14 60 and 15, having a flat intermediate portion and cylindrical end portions. The links 82 have bosses 86 around the openings 84, which bosses extend through slots 87 in the frame end plates 18 and 19. Outside of the end plate 19, a wide faced gear 90 is mounted to rotate upon the cylindrical portion of rod 85, while beyond the gear 90 there is an anti-friction roller 91. A similar roller is mounted 65 to turn upon the opposite end of the rod 85, and these two rollers run in cam grooves 92 in the end members 36 and 37 of the blanket cylinder. Consequently, as the cylinder revolves the cam 70 slots cause the bosses 86 on the links 82 to move inwardly and outwardly in the slots 87 of the frame members. In the end member 36 of the 75 blanket cylinder directly adjacent the cam groove

92, I mount a toothed rack 93 with which the gear 90 meshes. Accordingly, as the blanket cylinder revolves and the rod 85 moves inwardly and outwardly, the gear 90 carried by the rod rotates.

Three inking rolls 94, 95 and 96 are carried 5 in alignment by means of a pair of rails 97. Each of these rails is pivotally mounted at one point upon the cylindrical end portions of rod 85, and at another point by means of a circular boss 98 which is rotatably mounted in the opening 79 of link 74. Each of the rails 97 therefore in effect swings upon the two links 82 and 74, and its motion is such that it remains at all times parallel to a given plane or line, owing to the fact that the distance between the pivot point of the link 15 82 and the connection of the rail therewith is the same as the distance between the pivot point of link 74 and the connection of the rail therewith. These rails carry three pairs of guides 99, 100 and 101, within which slide the flattened ends of shafts 20 102, 103 and 104 upon which the rolls 94, 95 and 96 respectively revolve.

Upon the outer ends of rails 97 there are mounted yokes 105 which are adjustable to a slight extent longitudinally of the rails by means of 25 adjusting screws 106. Each of these yokes is formed at its ends with journals 107 in which shafts 108 are mounted for both longitudinal and rotational movement. Fixed to the shafts 108 are rolls 109. On one end of each shaft 108 there is 30 a spur gear 110 which meshes with the wide faced gear 90, while spaced away from the gear 110 a short distance is a collar 111. The annular space between each of the gears 110 and the corresponding collar 111 constitutes a groove into which 35 extends an arm 112 of a rocking yoke, see Fig. 18. This yoke comprises a circular member 113 which is mounted to rock on a pair of trunnions 114 that are carried by brackets 115 mounted in the frame end plate 19. On a diameter at right angles to the 40 axis of trunnions 114 a pair of anti-friction rollers 117 are carried by the yoke, and these rollers run upon a cam 118 which forms an integral part of the end plate 37 of the blanket cylinder. Accordingly, as the cam 118 revolves with the blanket 45 cylinder, it causes the yoke 113 to oscillate upon its trunnions 114. The yoke arms 112 therefore move the shafts 108 back and forth longitudinally in opposite directions, giving to the rolls 109 an oscillating motion, while they rotate, due to the 50 rotation of gear 90.

The oscillating rolls 109 have frictional contact at all times with rolls 96 and 95, roll 96 being urged into engagement by suitable spring means, such as is indicated at 119 in Fig. 14, and the 55 three rolls 78, 94 and 95 being pressed into frictional contact with each other and with the rolls 109 by suitable spring means on the links 74, as for instance the coil springs 120 anchored in the links and exerting a pull upon slide blocks 121. 60 Because of such frictional contact, all of the rolls 96, 95, 94 and 78 are driven from the rolls 109 at all times, and the roll 78 is driven from the roll 109 while those two rolls are in contact with each other. Consequently, ink taken by the 65 doctor roll 10 from the fountain roll 54 when the parts are in the position of Fig. 1, is transferred to roll 78 when the parts are in the position of Fig. 7, and thence passes along rolls 94, 95 and 109 to roll 96.

To one side of the inking mechanism I support upon the tray 23 a water reservoir 122 from which extends wicking or the like 123. This reservoir and the wicking protruding therefrom are arranged to be exposed to a greater or lesser 75

degree to the air circulating in the blanket cylinder by virtue of the movement of the vanes 39. Any suitable means for varying the degree of opening may be employed, but in Fig. 9 I have illustrated for this purpose a flexible curtain 123' which extends over a pulley 124 and has a weight 125 tending to raise the curtain. The latter may be held in the desired position of adjustment by means of fastenings at its lower edge taking into 10 selected ones of a series of holes in the frame of the device, or in some part carried thereby.

Plate roll throw-off.—Referring now particularly to Figs. 3, 4, 16 and 17, it may be assumed that the stencil printing machine with a portion 15 of which the present invention may be used, is provided with means for holding the impression roller 13 out of operative position when no sheet is being fed. Such mechanism works in opposition to the springs 16, and holds the lever 14 down 20 to the position indicated in Fig. 17 whenever a sheet of paper fails to enter the machine at the proper time. The lever 126 is a part of the mechanism above referred to, being pivoted at 127 and having its free end bearing upon the top of lever 25 14. The foregoing is a known construction, being illustrated and described in the Dick patent herefore mentioned.

I mount upon the frame of my unit a lever 128, pivoted at 129, the free end of this lever resting upon the free end of lever 126 and following the movements thereof, due to the action of spring 130. Another lever 131 is also pivoted at 129, and tends to move with lever 128, except that it has the capacity for slight independent movement, owing to the fact that its normal engagement with lever 128 is through a pair of spring plungers 132. At its upper end the lever 131 has a spear head 133. 134 is a pointed boss on the blanket cylinder, which is adapted to engage the spear head of lever 131 upon one side or the other, depending upon the position of lever 128 and the corresponding position of lever 131. The engagement ordinarily is merely enough to rock lever 131 through a slight angle 45 against the action of the spring plungers 132, which immediately return it to its former position. On the external frame of the unit there is a channel guide 135 within which is mounted a slide 136. The spear head 133 projects into 50 a cavity 137 in the rear face of the slide 136, which cavity is considerably wider than the spear head in order to permit the normal oscillation of the lever 131. The slide 136 has two positions, and it is held yieldably in either one of them 55 by a spring detent 138 carried by the frame, which detent takes into either one of two sockets 139 in the slide. 140 is a cylindrical rod which is fixedly mounted in the frame members. It is surrounded by a sleeve 141 with an eccentric bore, 60 and the plate cylinder 47 rotates upon this sleeve. At one end of the sleeve there is a gear 142 which meshes with a gear 143 of a diameter twice that of gear 142. The gear 143 turns upon a pin 144 which is fixed in the frame. On its inner side this gear 143 is provided with a series 65 of four radial slots 145. In aligned holes in the ends 45 and 46 of the plate cylinder I mount a rod 146, which is urged toward the position of Fig. 4 by a coil spring 147, its movement in that 70 direction being stopped by a pin 148. On the rear face of slide 136 there is a cam 149 which is adapted to engage the rod 146 and shift it longitudinally when the slide is in the proper position for that purpose. The blanket and plate 75 cylinders are operatively connected by gears 150

and 151, which have a two to one ratio. The teeth of the gears are long enough to permit the desired separation of the cylinders without going out of mesh. When the cam 149 is brought into operative position, the rotation of the plate cylinder causes the rod 146 to ride up onto the cam and forces the opposite end of the rod into one of the radial grooves 145. The rotation of the plate cylinder then causes the rod to turn gear 143 through an angle of 90°, when the rod leaves 10 the groove. This 90° rotation of gear 143 produces a 180° rotation of gear 142, and a similar rotation of eccentric sleeve 141. The slide 136 carries two oppositely directed spring pressed detents 152 and 153. When the slide is shifted 15 from the position of Fig. 4 to that of Fig. 16, detent 152 is withdrawn from a hole in sleeve 141, and detent 153 is drawn into contact with the sleeve. As soon as the 180° rotation of the sleeve is completed, detent 153 snaps into the 20 same hole and secures the sleeve against further rotation. When the movement of the slide is reversed the detent 153 is withdrawn and the detent 152 moves into contact with the sleeve ready to enter the hole as soon as the rotation of the 25 sleeve is completed.

The position of the parts in Fig. 3 is that which they occupy during normal running. In Fig. 17 they are shown in the positions which they occupy when the plate cylinder is thrown out of engagement with the blanket cylinder, the lever 126 at this time being lowered below the position which it occupies in Fig. 3. The movement of lever 128 from one position to the other may of course be accomplished by hand, but it is primarily my intention to have this movement performed automatically whenever the lever 126 is raised or lowered in connection with a sheet detector mechanism of the paper feed, such as previously referred to. A latch 154 may be used 30 to hold lever 128 in its raised position of Fig. 3, that is by swinging the handle of the latch to the right, as viewed in that figure, the lever 131 being thereby held in the position of Fig. 3, or the handle of latch 154 may be swung to the 35 left until it engages and pushes the lever 131 to the left and holds it in the position of Fig. 17, the lever 128 being then held in its lowered position by the lever 131. The latch 154 is intended for use only when the machine is being 40 set up for a job of printing, or when it is being 45 cleaned or the like.

For the convenient cleaning of the inking mechanism, the unit is so arranged that benzene or other cleaning fluid may be poured over the 50 inking rolls, being then discharged into the tray 23, and flowing thence through the trough 25 into the sump 24. A siphoning tube 155 extends from a position near the bottom of the sump upwardly into and through an opening 156 in 60 the hub 28 of the end member 19 of the frame. Consequently, as soon as the level of the liquid in the sump and tray reaches the opening 156, the liquid will be siphoned out down to the bottom of the tube 155. Any sludge that collects in 65 the sump can be drawn off by removing the plug 26.

In Fig. 19 I have shown a modification wherein 70 dampening rolls 157, 158 and 159 are mounted in the external frame members above the plate cylinder. The rolls 158 and 159, which contact with the plate 44, may be felt-covered, and the roll 157 may be of brass. Such rolls may be employed in the event that ordinary lithographic ink is used, and the air moistening means here- 75

tofore described is omitted. A small amount of water poured upon the brass roll 157 is sufficient for a considerable run.

Operation.—The operation of the unit, in connection with a portion of the stencil printing machine with which the invention may be employed, will be largely apparent from the foregoing description of the mechanism. When the operator desires to employ the offset printing unit, he removes the stencil cylinder of the machine, puts the unit in position between the standards 11, inserts the supporting elements 33 and 34 through the bearings 12 in the standards, and screws the supporting elements into the frame hubs, thereby fixing the unit in position. When the printing plate 44 has been mounted upon the plate cylinder, and the machine otherwise made ready for operation, the blanket cylinder is revolved by power or hand, as the case may be, and the paper sheets fed through the machine, in a manner apparent to those skilled in the art. Ink is applied to the plate 44 by the inking roll 96 during approximately one-half of the rotation of the blanket cylinder. As the forward edge of the blanket 41 approaches the plate cylinder the cam groove 92 acts through anti-friction rollers 91 to carry rod 85 inwardly, thereby swinging links 82 and 74 to the positions of Fig. 7 and withdrawing the roll 96 out of the path of the casting 38 and accompanying parts. This motion of links 74 pulls links 71 downwardly, bringing the two rolls 78 and 70 into contact, thereby rotating roll 70 and causing the ink thereupon to be wiped over the surface of roll 78, by which it is transferred through the intermediate rolls to roll 96. Further rotation of the blanket and plate cylinders causes the inked image upon plate 44 to be transferred to blanket 41, this operation being illustrated in Fig. 7. As the forward edge of the blanket approaches impression roller 13, a sheet of paper is fed into position above the impression roller and the latter rises to press the paper against the blanket for the printing operation. A cam plate 160 on the blanket cylinder permits the springs 16 to act at the proper time. The movement of the vanes 39 carries a supply of air past the opening in the moistening apparatus 122. The air thereby moistened flows over the ink on the inking rolls, particularly roll 96, enabling the ink to extract the necessary moisture from the air. It will be apparent that the yoke mechanism, illustrated in Fig. 18 of the drawings, oscillates the rolls 109 continuously, whether they are in the inner or outer position, the relation of the yoke arms to the shafts 108 when the rolls are withdrawn inwardly being indicated in dotted lines in Fig. 18.

The operation will be continuous so long as sheets are properly fed to the machine. If there should be an interruption in the sheet feed, the free end of lever 126 would drop and lever 128 would follow it. Lever 131 would then swing toward the left into the position shown in Fig. 17. The boss 134 upon its next approach would then move to the right of the spear head 133 and shift the lever 131 to the left, carrying with it the slide 136 which moves far enough to permit spring detent 138 to leave the lower one of sockets 139 and enter the upper one. When this movement occurs, cam 149 is brought into the path of rod 146, and causes the opposite end of the rod to engage with one of the radial grooves 145, operating as heretofore described to turn eccentric sleeve 141 through an angle of 180°, separating the plate cylinder from the blanket cylinder

inder without interrupting the geared travel of the plate cylinder. The parts thereafter remain in the position of Fig. 17 until the feed of sheets is resumed, whereupon the levers 126 and 128 rise again to the positions shown in Fig. 8, causing the lever 131 to move back into the position of that figure. When the boss 134 on its next revolution approaches the spear head 133 it contacts the inner side of the same and shifts the lever 131 to the right, shifting the slide 136 accordingly, and causing the rod 146 to ride over the cam 149 so as to engage the next radial groove 145 in gear 143 and produce through the mechanism previously described a second 180° rotation of sleeve 141, whereby the plate cylinder is returned to engagement with the blanket cylinder and the transfer of the image to the blanket is resumed.

While I have described and illustrated my invention as applied to a unit which may be inserted into a known stencil printing machine, I desire it to be understood that many of the features of the invention herein disclosed are equally susceptible of application to complete offset printing machines having no mechanical connection with other printing machines of any character.

Having thus described my invention, I claim:

1. In combination, a frame having aligned supporting elements adapted to be received in aligned bearings, a blanket cylinder mounted for rotation upon said frame, means for driving said cylinder, and a plate cylinder carried by said frame in position to cooperate with said blanket cylinder.

2. In combination, a frame comprising end members, said end members having aligned supporting elements adapted to be received in aligned bearings, a blanket cylinder mounted upon said frame for rotation about an axis within said aligned supporting elements, and a plate cylinder carried by said frame in position to cooperate with said blanket cylinder.

3. In combination, a frame having aligned supporting elements adapted to be received in aligned bearings, a hollow blanket cylinder surrounding the intermediate portion of said frame, the said blanket cylinder having rotative bearings upon said aligned supporting elements, frame extensions outside of said blanket cylinder, and a plate cylinder carried by said extensions in position to cooperate with said blanket cylinder.

4. In a unit for printing machines, a frame, means for supporting said frame exclusively comprising aligned supporting elements adapted to be received in aligned bearings, a hollow cylinder mounted for rotation upon said frame, means for driving said cylinder, a plate cylinder carried by said frame adapted to contact with the said hollow cylinder intermittently, and inking mechanism also carried by said frame and adapted to apply ink to said plate cylinder while it is out of contact with the said hollow cylinder.

5. In combination, a frame having aligned cylindrical supporting elements adapted to be received in aligned bearings, the center of gravity of said frame lying below the axis of said aligned supporting elements, a hollow cylinder mounted upon said frame for rotation about said cylindrical supporting elements, and a plate cylinder carried by said frame exclusively and adapted to contact with the said hollow cylinder.

6. In combination, a frame comprising aligned horizontal supporting elements, aligned bearings carried by the frame, a hollow cylinder mounted

- to rotate upon said bearings, inking mechanism carried by said frame substantially within said hollow cylinder, a plate cylinder carried by said frame externally of said hollow cylinder, said hollow cylinder being open throughout a peripheral portion thereof, and means for causing said inking mechanism to apply ink to said plate cylinder through the opening in said hollow cylinder as the cylinders rotate.
10. 7. In combination, a frame comprising aligned horizontal supporting elements, aligned bearings carried by the frame, a hollow cylinder mounted to rotate upon said bearings, inking mechanism carried by said frame substantially within said hollow cylinder, said inking mechanism comprising an ink applying roller, a plate cylinder carried by said frame externally of said hollow cylinder, said hollow cylinder being open throughout a peripheral portion thereof, and means for projecting said ink applying roller into contact with said plate cylinder through said opening and for retracting said ink applying roller and holding it within the hollow cylinder while the latter is in contact with the plate cylinder.
15. 8. In an offset printing machine, a frame having horizontally arranged aligned supporting elements, a hollow blanket cylinder rotatable about said supporting elements, inking mechanism carried by said frame substantially within said hollow blanket cylinder, and an air moistener carried by said frame within the blanket cylinder.
20. 9. In an offset printing machine, a frame having horizontally arranged aligned supporting elements, a hollow blanket cylinder rotatable about said supporting elements, inking mechanism carried by said frame substantially within said hollow blanket cylinder, an air moistener carried by said frame within the blanket cylinder, and means for creating a draft of air over said moistener and thence to said inking mechanism.
25. 10. In an offset printing machine, a frame having horizontally arranged aligned supporting elements, a hollow blanket cylinder rotatable about said supporting elements, inking mechanism carried by said frame substantially within said hollow blanket cylinder, an air moistener carried by said frame within the blanket cylinder, and a plurality of vanes on the inner side of said blanket cylinder for creating a draft of air past said moistener and over said inking mechanism.
11. In a printing machine, a hollow cylinder, a plate cylinder arranged for cooperative movement with said hollow cylinder, said hollow cylinder being open throughout a peripheral portion thereof, a fixed frame within said hollow cylinder, inking mechanism carried by said frame, said mechanism comprising a series of rollers, means actuated by said rotating hollow cylinder for driving said rollers, and means for moving said rollers inwardly and outwardly to project the outermost roller through said opening into contact with said plate cylinder and to retract the said roller within the hollow cylinder while the latter is in contact with said plate cylinder.
15. 12. In an offset printing machine, a frame having horizontally arranged aligned supporting elements, a hollow blanket cylinder rotatable about said supporting elements, said frame intermediate the ends of the blanket cylinder comprising a tray and a sump in communication therewith, inking mechanism carried by the frame above said tray, and a siphoning tube extending from said sump upwardly through one of said aligned supporting elements.
20. 13. In an offset printing machine, a plate cylinder, an inking mechanism, a container therefor permitting the application of ink to said plate cylinder, and means for maintaining a substantially constant degree of humidity of the air within said container.
25. 14. In a printing machine, inking mechanism, a frame upon which said mechanism is mounted, said frame having at the ends thereof two supporting elements arranged in alignment, a hollow cylinder rotatably mounted upon said supporting elements and surrounding said inking mechanism in the normal position of the latter, a printing plate adapted to move in printing relation with said cylinder, said hollow cylinder being open throughout a peripheral portion thereof, said inking mechanism comprising an ink applying roller, and means for projecting said roller through said opening into contact with said plate and for retracting said roller and holding it within the hollow cylinder while the latter is in contact with said plate.
30. 35. 40. 45. 50.
